UNITED STATES PATENT OFFICE.

AGOSTINO TOSCO AND PAUL SALINA, OF SAN FRANCISCO, CALIFORNIA.

FLUSH-OUT VALVE.

1,079,036.

Specification of Letters Patent. Patented Nov. 18, 1913.

Application filed March 22, 1913. Serial No. 756,125.

To all whom it may concern:

Be it known that we, AGOSTINO Tosco and PAUL SALINA, citizens of the United States, residing at San Francisco, in the county of San Francisco and State of California, have invented new and useful Improvements in Flush-Out Valves, of which the following is a specification.

This invention relates to a flushing apparatus for water-closets and the like, and particularly pertains to a flush-out valve therefor.

It is the object of this invention to provide a flushing apparatus for water-closets which is adapted to deliver the same amount of water upon every occasion and which operates to discharge a large flush at first to insure flushing the water-closet bowl, and a small flush at the last so as to properly fill the bowl and seal the trap.

Another object is to provide a flush-out valve which is simple and cheap in construction, efficient in operation, durable, and which may be easily and quickly removed and replaced at small cost when worn or damaged.

A further object is to provide a flush-out device of the type employing a hollow rubber ball as a valve, and to provide means for guiding and directing the ball to its seat after being unseated, so that it will not forcibly strike or impact the seat but will move gently to its seated position, thereby preventing the ball from becoming distorted and misshapen and consequently increasing its durability and efficiency.

Other objects will appear hereinafter.

The invention primarily resides in a flush pipe, having a valve seat formed thereon, a floating ball adapted to be held in place on the valve seat by the liquid in the flushing tank to which the flush pipe is attached, means for projecting the ball out of its seat, a cage in which the ball travels and formed to retain the ball out of its seated position until the liquid in the tank falls below a predetermined level, and so arranged as to direct the ball back to its seat on the surface of the liquid in a horizontal direction.

The invention consists of the parts and the construction and combination of parts as hereinafter more fully described and claimed, having reference to the accompanying drawings, in which—

Figure 1 is a side elevation of the invention, shown as applied to a flushing

tank, a portion of the latter being broken away. Fig. 2 is a plan view. Fig. 3 is a detail elevation on the line *a—a* of Fig. 1. Fig. 4 is a vertical section in partial elevation of a modified form of the invention as applied to a flushing tank with portions broken away.

In the drawings, A represents a tank of any suitable construction, and B is a flush pipe connected to the bottom thereof, the upper end of which connects with an overflow pipe 2 extending upwardly in the tank A and terminating at a suitable point therein. Formed on the flush pipe B, adjacent the bottom of the tank A, is a valve seat 3. This seat is circular in plan and is preferably arranged at an angle of approximately 45°, as shown in Figs. 1 and 4. The overflow pipe 2 extends vertically adjacent the upper edge of the valve seat 3 and mounted on the overflow pipe 2 is a sleeve 4, which is secured to the pipe 3 by means of set screws 5 or in any suitable manner. Mounted on the sleeve 4 is a wire cage, which is shown in Figs. 1 and 2 as comprising a series of horizontally extending wires 6 and 6' spaced a suitable distance apart and adapted to inclose a floating ball 7, preferably formed of rubber or similar material, which ball forms a valve and is adapted to rest on the valve seat 3; the upper horizontal wire 6 of the cage being arranged to normally retain the ball valve 7 in close proximity to the valve seat 3 in a submerged position when the tank A is filled with water or other liquid. The wire 6 is bent upwardly at its outer end, as indicated at 6a, to form a pocket adapted to receive the ball 7 and hold it against movement when the ball is projected thereinto, as will presently be described. The horizontal wires 6' serve as guides to confine the ball 7 against lateral movement; the wires 6—6' co-acting to confine the travel of the ball 7 to a horizontal direction.

In the form of the invention shown in Figs. 1, 2 and 3, the means for projecting the ball 7 out of its seat is shown as consisting of a downwardly extending arm 8, which is pivoted at 9 at its upper end to a sleeve 10, secured to the upper end of the overflow pipe 2 by means of a thumb screw 11, or in any other suitable manner. The lower end of the arm 8 is forked to form a pair of spaced parallel portions or prongs 12, which pass astride of the wire 6 and ex-

an equal amount of water on every occasion, and as before stated, an after-wash is effected by the breaking of the column of water entering the flush pipe B immediately 5 before the seating of the valve 7.

The principal feature of this invention resides in directing the ball 7 back to its seated position in a horizontal direction and in such manner that it will not strike the 10 valve seat 3 with a forcible impact, thus lengthening the life of the ball 7 and increasing its efficiency, as it has been found where floating rubber balls 7 have been employed as valves, that when they become dis- 15 torted and misshapen by impact with the valve seat they become ineffective and necessitate frequent renewal.

Having thus described our invention, what we claim and desire to secure by Letters Patent is:

In a flushing apparatus of the character described, a tank, a vertical overflow pipe located therein and a flushing discharge pipe

with which said overflow pipe connects at the lower end, a valve seat connecting with 25 the discharge pipe out of line with the overflow and at an angle of approximately forty-five degrees, a buoyant spherical valve, an open wire cage by which the valve is normally directed upon the seat, an arm contacting with the ball, and lever connections by which the arm is actuated to throw the ball diagonally out of line with the seat, the upper member of said cage forming concave 30 rests to retain the ball until the water level 35 is depressed sufficiently to allow the ball to disengage and return to its seat.

In testimony whereof we have hereunto set our hands in the presence of two subscribing witnesses.

AGOSTINO TOSCO.
PAUL SALINA.
